UNITED STATES PATENT OFFICE.

JOSEPH JUDGE, OF PITTSSTON, PENNSYLVANIA.

STEAMING-CRATE.

1,390,911.

Specification of Letters Patent. Patented Sept. 13, 1921.

Application filed October 24, 1919. Serial No. 332,976.

To all whom it may concern:

Be it known that I, JOSEPH JUDGE, a citizen of the United States, residing at Pittston, in the county of Luzerne and State of Pennsylvania, have invented new and useful Improvements in Steaming-Crates, of which the following is a specification.

This invention relates to crates or racks for holding spools of silk for steaming during the process of manufacture.

In steaming silk thread it is the usual custom to wind the silk upon spools, which are known to the trade as "iron heads," in that the heads of the spools are formed of iron. When the silk is subjected to the steaming process, rust, resulting from the moisture of the steam, frequently forms on the spool heads and runs down on the silk of the spools immediately below.

It is the purpose of the present invention to overcome this disadvantage by arranging the spools in racks formed in the crate and separated by a partition, which forms a roof or protection for the spools beneath from the rust of the spools above.

A further object is the provision of novel means for holding spools within the crate in a manner to permit of their ready insertion and removal when desired.

Other objects and advantages of the invention will appear as the following description is read in connection with the accompanying drawings.

In the drawings:

Figure 1 is a front elevation of a steaming crate embodying the present invention.

Fig. 2 is a rear view of the same.

Fig. 3 is a vertical transverse sectional view.

Referring to the drawings in detail, wherein like characters of reference denote corresponding parts, the crate comprises a frame 10, which is of rectangular formation and is designed to be placed in a steaming room after having been filled with spools of silk, for the purpose of subjecting the latter to a steaming process, as is well known in the art. The frame 10 is divided into a plurality of spool receiving racks by means of spaced partitions 11, the latter extend-

ing longitudinally of the frame from end to end. Each of these racks is provided along its upper rear edge with a retaining strip 12, of a size sufficient to prevent the passage of a spool through the rear of the rack. The front face of the rack is also provided with a retaining strip 13, this last mentioned strip, however, being secured along the lower portion of the rack and extending from one end of the frame to a point adjacent to and spaced from the opposite end of the frame to provide an entrance 14, by means of which the spools may be inserted in the rack.

The width of the frame and the partitions 11 are such that the moisture resulting from the steam will not carry the rust from one row of spools to the silk upon the spools below, at the same time steam being permitted to strike the silk around all sides of the spool, so that the latter will be thoroughly steamed. The spools may be readily removed by sliding them along the racks and through the openings 14.

The rack is adapted to hold various kinds of spools, such as "iron heads" previously referred to, some of which have a pin extending from each end thereof and some of which are provided with openings extending axially therethrough, or spools of wooden construction.

The invention is susceptible of various changes in its form, proportions and minor details of construction and the right is herein reserved to make such changes as properly fall within the scope of the appended claim.

Having described the invention, what is claimed is:

A device of the class described comprising a rectangular frame, spaced horizontal partitions formed integrally therewith and extending longitudinally therein, a retaining strip formed along the upper rear edge of each partition and a second retaining strip formed along the lower front edge of each partition and terminating short of one end of said frame.

In testimony whereof I affix my signature.
JOSEPH JUDGE.
